CARBURETOR

Charles Julien Erade, Brussels, Belgium

Application May 29, 1931, Serial No. 541,054,
and in Belgium June 17, 1930

4 Claims. (Cl. 261—49)

My invention relates to a carburetor for internal combustion engines, particularly those employed on motor vehicles, which permits the most suitable mixture of air and fuel to be obtained automatically for all working conditions of the engine, and also permits a rapid acceleration to be obtained whatever be its speed or its load.

For this purpose means have been provided in order to obtain automatically in a carburetor the preferred mixture curve or a curve approaching it, for example that which indicates a rich mixture for small and large openings of the carburetor, and a less rich or economical mixture at mean openings of the carburetor, that is to say those most employed in the case of a motor vehicle.

With a view to obtaining this result a constant level carburetor has been provided, combining opening or closing means controlling different orifices for the admission of air, fuel, and the outlet of the gases simultaneously and in the required portions, in order to supply the engine with the most suitable mixture as regards quality and quantity, whatever be its working conditions.

According to the invention, the carburetor is formed by a main cylindrical duct in which are provided two butterfly valves, one for regulating the air admission and the other for regulating the delivery of the gases. Two ducts open out towards the centre of the main duct, the lower one of these ducts comprising a fuel admission jet, and the upper of these two ducts serving for the admission of additional air, and through which a part of the air drawn in by the engine is directed so as to produce a restraining action on the delivery of fuel supplied by the jet. The delivery of fuel is proportional to the vacuum existing in the carburetor and resulting from the suction which is a function of the speed of the engine.

The speed of an engine can increase under two conditions of working, either under constant load by an increase in the degree of opening of the carburetor throttle, or by a reduction on the load on the engine, the degree of the throttle valve remaining constant. Consequently the carburetor requires two combinations for the fuel, the first for the variable opening of the throttle and the second for the constant aperture of the throttle.

In the case of very wide limits of speed of the engine, a variable jet has also been provided, the progressive opening of which is combined

with that of the throttle valves or closing members controlling the air admission or gas outlet orifices.

The carburetor also permits the petrol supplied to be completely restrained if desired by a suitable combination of the control of the opening of the levers admitting restraining air and gas in order to stop the delivery of the carburetor so as to utilize the engine as a brake for the vehicle when going down hill without consuming fuel.

Some forms of construction of the subject of the invention are illustrated hereinafter simply by way of example with reference to the accompanying drawings, in which:

Figure 1 is a diagrammatic view of a carburetor showing two throttle valves provided in the main duct and comprising a restraining air duct having an adjustable aperture.

Figure 2 is a diagrammatic view similar to Figure 1 but comprising an adjustable needle valve in the duct.

Figure 3 is a sectional view of the form of construction shown in Figure 1.

Figure 4 is a sectional view taken on the line 4—4 of Figure 3, showing the construction of the regulating member controlling the orifice admitting restraining air.

Figure 5 is a detail view of the adjustable needle valve controlling the orifice of the duct when the carburetor is constructed according to the embodiment shown diagrammatically in Figure 2.

Figure 6 is a cross sectional detail view of a restraining air duct according to one embodiment of the invention.

Figure 7 is a side elevation of the same.

As shown in the drawings, the carburetor is formed by a tubular body 40 having a flange 41 for attachment to the engine. This tubular body is provided with two flaps or throttle valves 42 and 43 provided respectively for regulating the admission of noncarbureted air, and the outlet of the gases, the said flaps or throttle valves being connected together by means of a connection 44 pivoted on the one hand at 45 to the lever 46 of the valve 42, and on the other hand at 47 to the lever of handle 48 controlling the valve 43 (Figure 1).

In the interior and approximately at the center of the tubular body 40 enters a duct 49 provided with a jet 50 for the admission of the fuel, this duct communicating with the usual constant level chamber of a carburetor (not shown).

Above the jet 50 enters a second duct 51 slipped

over the end of the said jet and comprising an orifice 52 for the passage of the restraining air admitted through a lateral nozzle 53 provided in the mass of the main body 40, and preferably entering above and at the level of the latter (Figure 3).

At the lower part of the duct 51 is a cutaway part 54 permitting the passage of the carbureted mixture.

- 10 According to the form of construction shown in Figures 1, 3 and 4, the aperture of the jet remains constant, but the section of passage of the auxiliary nozzle 53 is controlled by a flap or rotary cock 60 connected by the levers 61 and 15 62 and the connection 63 to the control handle 48 of the throttle valve 43.

- As shown in Figure 5, the aperture of the duct 53 is constant but the calibrated orifice of the jet 50 is controlled by a movable and adjustable 20 needle valve 64 mounted to slide vertically in a collar 51a in the duct 51; this needle valve is controlled by means of the handle 48 through the levers 65, 66 and 67.

- Finally, in the form of construction shown in 25 Figure 2, the carburetor comprises the whole of the adjusting devices.

- In the above description and construction of the different members comprising the carburetor forming the subject of the invention, it will be 30 understood that by a judicious and proportional adjustment of the air and the fuel admission and gas outlet apertures, it is easy to obtain at all times the most favourable mixture for the different conditions of work of the engine.

- 35 The vacuum and consequently the delivery of fuel in the mixture chamber depend upon the aperture of the throttle 43 through which the gases pass out and of the throttle 42 admitting the main air so that the aperture of these throttles will be regulated in such a way that the 40 vacuum will be sufficient to permit the necessary delivery of petrol from the jet. The relative apertures of the two throttles are regulated by the length of the corresponding levers 46 and 45 48 of the throttle valves 42 and 43 connected together by the jointed connection 44.

- In order to obtain the economical mixture for medium openings of the gas outlet throttle valve 43, the admission of restraining air through the 50 duct 53, 51 will be regulated and this air will act by pressure according to its speed upon the delivery of the jet 50. The adjustment of restraining air is effected by means of the cock 60 controlled by the lever 61 connected by the pivoted connection 63 to the lever 62 of the gas outlet throttle valve 43, the said lever being rigid with the control lever 48. The length and the arrangement of the control levers 61 and 62 will be regulated in such a way as to produce the 55 restraining action upon the delivery of the jet which will produce an economical mixture for medium conditions of working of the engine, and the less intense restraining action which produces an engine mixture during slow speed running and at high speeds of the engine.

- The jet 50 will be chosen sufficiently large for the delivery required at the maximum power of the engine. For the very wide limits of speed of the engine in revolutions per minute which produce very great differences in delivery, it may be necessary to employ an adjustable delivery jet. For this case the arrangement shown in Figures 2 and 5 has been provided in which a movable and adjustable needle valve 64 is provided for 70 controlling the outlet orifice of the jet and con-

sequently of the fuel delivery. Pivoted levers 65, 66 and 67, suitably arranged and designed, are actuated by the control lever 48 permitting the height of the needle valve to be varied in the aperture of the jet 50, thus varying the section 80 of the outlet passage for the fuel.

This arrangement may be employed in combination with the adjustable admission of restraining air, as shown in Figure 2.

In the embodiment shown in Figs. 6 and 7 the means used for controlling and regulating the inlet aperture of the restraining air duct 51 consist in providing in the top portion of said duct a spindle 68 around which may be rotated a sleeve 69 rigid with a disc 70 furnished with a suitable aperture 71 adapted to register with an aperture 72 machined in the side wall of the duct 51, upon operation of the lever 61 connected by the connection 62—63 to throttle valve 43.

If desired, a removable washer 73 may be interposed between the disc 70 and the duct body 51 (Fig. 6), said washer being provided with an air admitting orifice 74.

This arrangement enables a ready fitting of the washer having the most suitable restraining 100 air admitting orifice.

As shown in Figure 6, the cross sectional area of the air admission orifices is adjustable by means of a cap or cock 92 having several ports 93, said cock being formed with an operating 105 lever which may be actuated in any convenient manner.

In all the embodiments hereinbefore described, the delivery orifice 50a of the spray nozzle 50 or the orifice through which the fuel is supplied into 110 the mixing chamber may be of conical or crater shape, so as to confine the restraining air towards the fuel jet.

Moreover, the cross sectional area between the said orifice 50a of the spray nozzle 50 and the 115 outlet orifice 51c of the restraining air duct 51 may be adjusted in any convenient way.

Finally the carburetor may be provided with any desired number of spray nozzles, one or more of which may be acted upon by restraining air, 120 as described.

What I claim is:

1. A carburetor for internal combustion engines comprising a tubular body having a flange for attachment to the engine, a first throttle valve 125 in this tubular body for controlling the main air supply, a second throttle valve in the tubular body for controlling the outlet of the mixture, a lower fuel duct connected to the under side of the tubular body at about its center, an upper auxiliary 130 air duct coaxial with the lower duct and secured to the upper side of the tubular body, a valve in this upper duct for controlling the passage of air in this duct, a control member for this valve and a common control for simultaneously varying 135 the admission of air in this auxiliary air duct, the main air admission and the outlet of mixture, means other than the said valve in the upper duct for controlling the volume of air admitted in said auxiliary air duct, and means for varying 140 the aperture of the fuel admission jet.

2. A carburetor for internal combustion engines comprising a tubular body having a flange for attachment to the engine, a first throttle valve 145 in this tubular body for controlling the main air supply, a second throttle valve in the tubular body for controlling the outlet of the mixture, a lower fuel duct connected to the under side of the tubular body at about its center, an upper auxiliary air duct coaxial with the lower duct and secured 150

to the upper side of the tubular body, a first aperture in this upper duct communicating with the atmosphere, a control member for said aperture, a second aperture in this upper duct, a control member for controlling the communication of said second aperture with the atmosphere, said latter control member being connected to a common control for simultaneously varying the admission of auxiliary air, the admission of main air and the outlet of mixture.

3. A carburetor for internal combustion engines comprising a tubular body having a flange for attachment to the engine, a first throttle valve in this tubular body for controlling the main air supply, a second throttle valve in the tubular body for controlling the outlet of the mixture, a lower fuel duct connected to the under side of the tubular body at about its center, a needle longitudinally displaceable in the fuel admission duct, an upper auxiliary air duct coaxial with the lower duct and secured to the upper side of the tubular body, a valve in this upper duct for controlling the passage of air in this duct, a control member for this valve, and a common control for simultaneously varying the ad-

mission of air in this auxiliary air duct, the main air admission and the outlet of mixture, and means for simultaneously displacing the fuel duct control needle with the aforesaid common control.

4. A carburetor for internal combustion engines comprising a tubular body having a flange for attachment to the engine, a first throttle valve in this tubular body for controlling the main air supply, a second throttle valve in the tubular body for controlling the outlet of the mixture, a lower fuel duct connected to the under side of the tubular body at about its center, a needle longitudinally displaceable in the fuel duct, a control member for said needle, an upper auxiliary air duct coaxial with the lower duct and secured to the upper side of the tubular body, a valve in this upper duct for controlling the passage of air in said duct, a control member for this valve, and a common control for simultaneously actuating the fuel duct control member with the valves controlling the auxiliary air, the main air supply and the outlet of mixture.
